Primary Examiner — Ricky Pham(74) *Attorney, Agent, or Firm* — John F. Vodopia(57) **CLAIM**

The ornamental design for the combination baking pan and cooling rack, as shown and described.

DESCRIPTION

FIG. 1 is a top perspective view of our design for a combination baking pan and cooling rack;

FIG. 2 is an exploded top perspective view thereof;

FIG. 3 is a top plan view thereof;

FIG. 4 is a bottom plan view thereof;

FIG. 5 is a left side view thereof; the right side view is a mirror image of the left side view; and,

FIG. 6 is a front side view thereof; the back side view is a mirror image of the front side view.
